(57) **CLAIM**

The ornamental design for the vehicle waste hose support device, as shown and described.

DESCRIPTION

FIG. 1 is a front perspective view of the vehicle waste hose support device; and

FIG. 2 is a front plan view thereof; and

FIG. 3 is a rear plan view thereof; and

FIG. 4 is a left side view thereof; and

FIG. 5 is a right side view thereof; and

FIG. 6 is a top view thereof; and,

FIG. 7 is a left side view thereof in an extended position.

Wherein the dotted lines illustrated herein form no part of the claimed design and are illustrated for the purpose of use and environment.
